JUMPER FOR INTERCONNECTING SPACED ELECTRIC TERMINALS

James M. De Montmollin, Griffin, Ga., assignor to Southern States Equipment Corporation, a corporation of Georgia

Application February 24, 1953, Serial No. 338,385

1 Claim. (Cl. 339—19)

This invention relates to electric jumpers and more particularly to jumpers adaptable for use in conjunction with a wide range of circuit voltages.

Power fuses and cutouts as well as switches of the disconnect or air break type must be taken out of service occasionally for inspection, maintenance, repair, or replacement and should be operated mechanically at regular intervals so as to facilitate proper mechanical operation under all service conditions. Such maintenance procedures ordinarily must be conducted without interrupting the flow of load current. In order to maintain an uninterrupted flow of load current, it has been the practice to shunt the service apparatus with a jumper before operating or removing the service equipment from the circuit associated therewith.

A principal object of this invention is to provide an electric jumper which inherently is adaptable for use under a wide range of voltage conditions.

Another object of this invention is the provision of an improved electric jumper which establishes and maintains a path of high electrical conductivity between two spaced terminals interconnected by the jumper.

Still another object of this invention is to provide an improved electric jumper which is simple in construction and which affords a high degree of safety and reliability.

For interconnecting a pair of spaced electric terminals, this invention in one form comprises a first contact engageable with one of the terminals, a second contact telescopically related with the first contact and having a plurality of laterally extending contact projections spaced thereon for selectively engaging the other terminal, and biasing means tending to impart relative movement to the contacts in a direction axially thereof. According to one feature of the invention, the contacting portion of each of the contact projections is spaced from the axis of the contacts so that the biasing means causes a bending moment to be applied to the contacts and thus maintains adequate contact pressure therebetween thereby to establish a path of high electrical conductivity between the terminals bridged by the jumper. The current-carrying capacity of the jumper may be increased by mounting suitable finger contacts on one of the contacts for slideable engagement with the other contact and suitable stop means may be provided to limit the relative movement between the contacts.

For a better understanding of the invention reference may be had to the following description taken in conjunction with the accompanying drawings in which Fig. 1 is a plan view of a jumper constructed according to the invention and mounted in its service position so as to interconnect a pair of spaced electric terminals, Fig. 2 is a side view of a jumper constructed according to the invention, and Fig. 3 is a cross-sectional view of a portion of the jumper shown in Figs. 1 and 2 viewed from the direction in which Fig. 1 is viewed.

With reference to Fig. 1 a pair of insulators 1 and 2 respectively support terminal assemblies 3 and 4. Terminal assembly 3 is electrically connected with circuit con-

2

ductor 5 and is provided with a hooked terminal element

6. Similarly terminal assembly 4 is electrically interconnected with circuit conductor 7 and is provided with a hooked terminal element 8. Terminals such as 6 and 8 are disclosed in detail and are claimed in application Serial No. 106,345, filed July 23, 1949, now Patent No. 2,689,944, dated September 21, 1954, by Thomas E. Curtis and assigned to the assignee of this invention. As is shown in Fig. 1 terminal assemblies 3 and 4 are interconnected by a power fuse 9. If it is desired to inspect the power fuse 9 and if removal of the fuse is necessary, service may be maintained by mounting the jumper 10 in position as shown in Fig. 1. With the jumper 10 in its service position fuse 9 may be removed and the load current is then supplied through the jumper 10. It is obvious that the fuse 9 could comprise a disconnect switch or some other piece of electric apparatus.

As can best be seen from Fig. 2 the jumper comprises a pair of telescopically related contacts 11 and 12. Affixed to the upper end of contact 11 is a ring element 13 which is secured to contact 11 by screws 14.

The contact 12, as is best shown in Figs. 1 and 2, is provided with a plurality of laterally extending hooked contact projections 15. The lower extremity of the contact 12 is constructed with a hollow portion 16 provided with a laterally extending slot 17 and a vertically disposed slot 18. The lower portion of contact 12 as will be readily understood from Figs. 1 and 2 is adapted for receiving the end of an operating rod having a lateral projection thereon which is movable upwardly through the vertical slot 18 and laterally through the slot 17 so as to form a disjunctive connection between the jumper and the operating rod.

As can best be seen from Fig. 3 the contact 11 is biased axially relative to the contact 12 by means of a tension spring 19 which at its upper end extends through an opening formed within a projecting tab 20 formed integrally with the ring element 13. The lower end of the spring 19 is connected with a pin 21 secured within the contact 12. As is shown in Fig. 3 the lower end of the contact 11 is in engagement with the pin 21 which acts as a stop therefor to determine the limit of travel of the contacts 11 and 12 in one direction relative to each other. For the purpose of determining the relative movement between the contacts 11 and 12 in the opposite direction a stop element 22 envelopes the stop pin 21 and is affixed to and movable with the contact 11 since its upper extremity is secured to the projection 20. Thus if the contact 11 is moved upwardly relative to the contact 12 against the bias of spring 19 the pin 21 ultimately will be engaged by the lower end loop of the stop element 22 so as to determine the limit of travel of contact 11 upwardly relative to contact 12.

In order to facilitate the establishment of a good electrical connection between contacts 11 and 12 and to increase the current-carrying capacity of the contacts, the contact 12 is constructed at its upper end with a plurality of slots 23 and a plurality of contact fingers 24 are secured by screws 25 to the contact element 12. Contact fingers 24 extend through the associated slots 23 so as to engage the contact 11 in a slideable relationship.

In order to mount the jumper in its service position, an operating rod is inserted into the lower end of the jumper and the whole assembly elevated until the ring element 13 envelopes the hook terminal 6. Thereafter the operating rod is pulled downwardly and one of the contact projections 15 is caused to engage the terminal 8. Thereafter the power fuse 9 may be removed and the circuit is maintained through the jumper 10 between the terminals 3 and 4. It will be understood, of course, that the fuse 9 could be a switch and that the purpose of mounting the jumper 10 in its service position could be to enable

an operator to operate the switch merely to determine its mechanical condition. Since the lower contact 12 is provided with a plurality of contact projections 15, it will be understood that jumpers constructed according to this invention are applicable to a wide range of space and voltage conditions.

It will also be understood that the contacting portion 26 of each of the contact projections 15 is spaced from the axis of the contacts 11 and 12 so that when the jumper is in its service position the action of the biasing spring 19 tends to impart a bending moment to the jumper assembly as a whole which tends to cause the outer surface of contact 11 to engage the inner surface of contact 12 by a pressure engagement thereby to aid in reducing the electrical resistance therebetween.

It will also be understood that the stop 21 limits relative movement of the contacts in both directions by respectively engaging the lower end of contact 11 and the stop 22.

In view of the above description it will be understood that by the invention I have provided an improved jumper which is readily adaptable to a wide range of voltage and space conditions, which affords good electrical conductivity between the terminals to be bridged by the jumper and which is relatively simple in construction and therefore reliable in application to a wide range of conditions.

While I have shown and described a particular embodiment of the invention I do not wish to be limited thereto and intend in the appended claim to cover all such changes and modifications as fall within the true spirit and scope of the invention.

What I claim as new and desire to secure by Letters Patent of the United States is:

A jumper for interconnecting a pair of spaced electric

terminals said jumper comprising a first contact engageable with one of said terminals, a second contact telescopically related with said first contact and having a plurality of laterally extending contact projections of conducting material spaced therealong for selectively engaging the other of said terminals, biasing means tending to impart relative axial movement to said contacts, the contacting portion of each of said contact projections being spaced from the axis of said contacts so as to cause a bending moment to be applied to said contacts thereby to maintain contact pressure therebetween, first stop means affixed to one of said contacts and engageable with the other of said contacts to determine the limit of relative movement of said contacts in one direction, and second stop means affixed to the other of said contacts and engageable with said first stop means to determine the limit of relative movement of said contacts in the other direction, one of said contacts having at least one slot therein in the telescoping part thereof, and a contact finger affixed to said one contact and extending through said slot slideably to engage the other of said contacts.
